UNITED STATES PATENT OFFICE.

CHARLES GEOFFREY SAWYER, OF SYDNEY, NEW SOUTH WALES, AND DESMOND FRANCIS GLYNN, OF MELBOURNE, VICTORIA, AUSTRALIA.

TROUSERS PRESS AND STRETCHER.

Application filed March 16, 1921. Serial No. 452,786.

To all whom it may concern:

Be it known that we, CHARLES GEOFFREY SAWYER, residing at Sydney, in the State of New South Wales, Commonwealth of Australia, and DESMOND FRANCIS GLYNN, residing at Melbourne, in the State of Victoria, Commonwealth of Australia, both subjects of the King of Great Britain, have invented new and useful Improvements in

10 Trousers Presses and Stretchers, of which the following is a specification.

This invention relates to an improved trousers press and stretcher devised in order to provide an appliance for maintaining 15 trousers in good condition when not in use.

The present invention provides a simple and economically constructed press and stretcher appliance having a main member of a flexible and springy nature, means 20 whereby a pair of trousers may be placed upon and folded over this member, means for resiliently holding in position the cuff portions of the trousers and means whereby said flexible member can be rolled up in contact with the trousers thereby stretching 25 the latter and maintaining an even surface transversely of each roll, and fastening means which retain said member and the trousers in a rolled condition.

30 The invention is illustrated in the accompanying drawings, wherein:

Figure 1 is a general view of the invention in the flat.

Figure 2 is a longitudinal section of Figure 1.

Figure 3 is an enlarged detail section on line A—A Figure 1.

Figure 4 is an enlarged detail section on line B—B Figure 1.

40 Figure 5 is an end elevation illustrating the invention when rolled up.

Figure 6 is a detail section on line C—C Figure 1.

Figure 7 is a detail section on line D—D Figure 1.

Figure 8 is a general view of a modified construction.

Figure 9 is a longitudinal section of Figure 8.

50 Referring to Figures 1 to 7, the numerals 10 and 11 indicate two superimposed sheets of flexible material, such as buckram, of ta-

pered formation—the upper ends being broader than the lower ends.

Interposed between the flexible sheets of 55 material 10 and 11 are a series of strips 12 of a springy nature. These strips may be of whalebone or the like but are preferably formed of spring steel cotton-covered and of the character commonly known as "crinoline steel."

The lower ends of said spring strips 12 are connected together by a transverse metal band 13.

The upper ends of the flexible sheets 10 65 and 11 with the interposed spring strips 12 are clamped between two transverse bars 14 and 15, in the lower of which bars a seating recess 16 is formed. Tacks 17 are driven through said sheets 10 and 11 and 70 said strips 12 into the lower bar 15, and screws 18 fastening the opposite ends of the bars 14 and 15 serve to clamp said sheets and spring strips firmly together.

The transverse connecting band 13 is interposed between two lower transverse bars 19 and 20, each of which has a recess 21 permitting the lower ends of the flexible sheets 10 and 11 to slide freely therein.

Two elastic bands 22 have their opposite 80 ends secured between said lower transverse bars 19 and 20 and pass across the face of one of said bars as illustrated in Figures 1 and 7.

Screws 23 are passed through the transverse bar 19, through the metal band 13 and the inturned ends of the elastic bands 22 and into the bar 20 thereby forming a firm fastening.

A strap 24 has one end secured to the 90 transverse metal connecting band 13 and it is furnished adjacent to its free end, which projects beyond the lower ends of the flexible strips 10 and 11, with a tab 25 and buckle 26.

In action the trousers are folded into their normal longitudinal creases and placed upon the upper side of the flexible element 10. The cuffs of the trousers are then slipped over the transverse lower bar 100 20 and beneath the elastic bands 22 which hold them in position. The upper portion of the trousers is then folded over the top of the upper transverse bars 14 and 15 and

is allowed to rest against the opposite flexible sheet 11. The appliance is then rolled with the trousers in contact with said flexible sheets, beginning from the broad upper end. This rolling action causes the garment to be stretched and maintains an approximately even pressure along the crease lines thereof. When the appliance with its contained garment is rolled up the end of the strap 24 is fastened to the buckle 26 of the tab 25, thereby forming a compactly and neatly rolled package.

In the modified construction illustrated by Figures 8 and 9, there is employed a single flexible sheet 10^a of approved springy material such as celluloid or thin spring metal having a polished surface, dispensing with the use of the spring strips 12 and the necessity for providing for a sliding movement of the flexible sheets. The upper end of the flexible and springy sheet 10^a is clamped between the transverse bars 14 and 15, while its lower end is fixedly secured between the lower transverse bars 19 and 20. A swivel attachment member 27 is fitted to the transverse bar 19 and receives a fitting 28 on the upper end of the strap 24.

The swivel connection of the strap with the bar 19 permits the former to be reversed, when the elastic bands 22 can also be reversed by extending over the lower ends and across the face of the lower bar 20, whereby the direction of rolling of the appliance can be reversed to prevent a permanent curved set being formed on the flexible sheet 10^a of the appliance. A similar result may be obtained in the construction illustrated by Figures 1 to 7 by reversing the elastic bands 22 in the manner described and by twisting the strap 24 to meet the requirements of the reversal of direction of rolling of the appliance.

What we do claim is:—

1. An improved trousers press and stretcher comprising, a flexible sheet clamped at each end between transverse bars and adapted to be rolled upon itself in contact with a garment supported thereon, means for resiliently holding the cuffs of the garment in connection with said sheet, and a fastening strap for maintaining the sheet in a rolled condition, substantially as described.
2. An improved trousers press and stretchers, comprising a flexible element adapted to be rolled upon itself in contact with a garment supported thereon, transverse bars at opposite ends of said flexible element, elastic bands connected to one of said bars to resiliently hold the cuffs of the garment in position, a fastening strap connected to one transverse bar, and means for reversing said elastic bands, substantially as and for the purpose described.
3. In an improved trousers press and stretcher a member comprising two superim-

posed sheets of flexible material, a plurality of spring strips interposed between said flexible sheets, a transverse band connecting said spring strips, a pair of transverse bars having a seating recess and functioning to clamp together the upper ends of said flexible sheets and of said spring strips, a pair of lower transverse bars having a slot permitting the slidable movement of the lower ends of said flexible sheets, means for clamping together said lower transverse bars, means for resiliently retaining in position the cuffs of the garment, and a fastening strap and buckle adapted to maintain the appliance in a rolled condition, substantially as described.

4. In an improved trousers press and stretcher a member comprising two superimposed sheets of flexible material, a plurality of cotton covered spring steel strips interposed between said flexible sheets, a transverse band connecting said spring strips, a pair of transverse bars having a seating recess and functioning to clamp together said flexible sheets and spring strips at one end, a pair of transverse bars having a slot permitting the slidable movement of the other ends of said flexible sheets, means for clamping together said latter transverse bars, reversible elastic bands resiliently retaining the cuffs of the garment in position on said flexible sheets, and a fastening strap and buckle adapted to maintain the appliance in a rolled condition, substantially as described.

5. An improved trousers press and stretcher, comprising a flexible element adapted to be rolled upon itself with a garment in contact therewith, rigid bars extending transversely at the opposite ends of said flexible element, means for resiliently holding the cuffs of the trousers in contact with the rigid bar at one end of the flexible element, and a fastening strap for maintaining the flexible element with the garment supported thereby in rolled condition substantially as described.

6. In a trousers press and stretcher, a flat resilient sheet member with the side edges converging from one end to the opposite end, rigid means extending transversely of and secured to the end of said member of greatest width, means extending transversely of said member adjacent the opposite end, for the clamping of the trousers at the leg end to said sheet, said trousers being adapted to be folded flat against the resilient member and the latter rolled upon itself with the trousers in contact therewith, and means to retain the resilient member in rolled condition.

7. In a trousers press and stretcher, a resilient sheet member, rigid means extending transversely of and secured to one end of said member, means extending transversely

of the sheet adjacent the opposite end for clamping of the trousers at the leg to the resilient sheet, the trousers being adapted to be folded flat against the resilient sheet 5 member and the latter rolled upon itself with the trousers in contact therewith, and means to retain the resilient member in rolled condition.

In testimony whereof we affix our signatures in presence of two witnesses.

CHARLES GEOFFREY SAWYER.
DESMOND FRANCIS GLYNN.
